UNITED STATES PATENT OFFICE.

BENJAMIN F. AUGUSTINE, OF BUFFALO, NEW YORK.

FLUID-MIXING DEVICE.

1,178,832.

Specification of Letters Patent. Patented Apr. 11, 1916.

Application filed September 23, 1911, Serial No. 650,979. Renewed March 4, 1916. Serial No. 82,270.

To all whom it may concern:

Be it known that I, BENJAMIN F. AUGUSTINE, a citizen of the United States, residing at Buffalo, in the county of Erie and State of New York, have invented certain new and useful Improvements in Fluid-Mixing Devices, of which the following is a specification.

This invention relates to a combined fluid mixing and controlling device.

One object is to provide a device particularly adapted for mixing combustion fluids embodying such characteristics that the mixed fluid possesses the requisite richness.

Another object resides in the provision of a device for mixing fluids for compression and subsequent combustion embodying among other characteristics means whereby the amount of one fluid mixed with another fluid is regulated with regard to the amount thereof required for mixing with the other fluid.

Another object is to provide a device adapted to mix air and gasolene or other fluids and provided with a valve which is operable under the influence of a vacuum or suction to permit of discharge of the fluids therefrom with the supply of the gasolene controlled by the amount of air discharged from the device whereby the fluids are properly proportioned with relation to each other.

Another object resides in the provision of a fluid mixing device embodying such characteristics as to provide for an efficient mixing of fluids, with means provided whereby the supply of one of the fluids may be stopped, and by ceasing the supply of this particular one of the fluids, cutting off supply of the remaining fluid or fluids.

A still further object is to provide a mixing device for efficiently mixing gasolene and air, the supply of gasolene for admixture with the air being regulated according to the discharge of the air from the mixing device.

It is still further designed to provide a mixing device particularly adapted for connection with a pump, compressor, combustion or other engine or device including means to provide for the admixture of air and gasolene or other fluids with one of the fluids supplied for admixture with the other according to the discharge of the fluids from the device.

With the above and other objects in view the present invention consists in the combination and arrangement of parts herein-after more fully described, illustrated in the accompanying drawing, and particularly 60 pointed out in the appended claims, it being understood that changes may be made in the form, proportion, size and minor details without departing from the spirit or sacrificing any of the advantages of the invention.

The figure is a sectional view showing my improved mixing device applied to a rotary compressor or vacuum creating device.

While my device may be used in various 70 arts, the preferred use is in connection with compressors for compressing fluids.

The rotary compressor illustrated in the figure is but one type of rotary compressor with which my improved mixing device may 75 be connected. As the compressor illustrated forms no part of this invention, I have illustrated merely sufficient structure of a compressor to point out the operation of my improved mixing device. With this understand- 80 ing it may be recited that the rotary compressor shown consists of a casing including a cylinder 5, an inlet chamber 6, a compressing chamber 7 and a base 8, the inlet and compression chambers being on op- 85 posite sides of a dividing wall 9 with the inlet chamber 7 provided with an inlet port 10 and the compression chamber provided with an outlet port 11. The cylinder 5 has a central chamber in which is located an 90 abutment 12 which latter has an eccentrically disposed cylindrical chamber 16. The outer face of the abutment is cylindrical and concentrically disposed relative to the axis of a driving shaft 13 on which is mounted 95 the rotatable piston carrier 14 provided with a plurality of pistons 15 which are adapted to slide radially relative thereto.

The abutment 12 engages the upper end 100 of the vertical dividing wall 9 and completes the separation of the inlet side of the compressor from the discharge side thereof so that the fluid passing through the compressor must pass through the cylindrical chamber 16 in the abutment. Formed in the abutment at the inlet side of the compressor is a circumferentially disposed slot 17 which communicates with one or more slots 18 on the inner side of the abutment by a flared 105 passage 19. These slots and said passage 110

extend preferably from a point adjacent to the vertical wall 9 to a point 20 which is above the center of the drive shaft 13.

On the discharge side of the compressor connection is made with the compression chamber 7 by providing the abutment with a discharge slot 22 which is similar in construction to the inlet slot or port 17. This discharge port 22 consists of a circumferential slot in the outer face of the abutment extending from the vertical wall 9 to a point 23 which is above the center of the cylindrical chamber. The inner face of the abutment at the discharge side of the compressor is provided with one or more slots 24 which may be similar to the slot or slots 18 there being a flared passage 25 connecting the slots 22 and 25 in the same manner as the passage 19 connects the slots 17 and 18. The compressor creates a suction or vacuum and it will be apparent, therefore, that the fluid drawn in through the inlet ports may be conveyed through the cylindrical chamber to the discharge ports, thence to the main compression chamber 7. From the main compression chamber the compressed fluid passes to a suitable receiver 28 or other device, there being a valve mechanism A between the compression chamber 7 and the receiver 28 which is operable under the influence of pressure in the compression chamber to permit passage of the compressed fluid to the receiver 28. When the fluid in the receiver 28 reaches a predetermined pressure it forces the valve mechanism A to closed position and a portion of the fluid passes through the conduit 29 to a relief valve mechanism B to operate the same to open it and permit the fluid in the compressor to circulate through the same by way of one or more ports 30-31 in the dividing wall 9.

As has been stated, the essential feature of my invention in this case resides in the fluid mixing device which in addition to efficiently mixing the fluid, also controls the supply of the fluid delivered to a compressor or to a combustion or other engine or device. To properly mix air and gas and control the supply of same to a compressor or the like I have provided my improved device, which, in the compressor illustrated in the accompanying drawing, is connected up with the casing of the compressor at the inlet port 10. This improved device has its casing 33 divided by a partition α into air and gas chambers b and c , respectively, with a controlling valve 32, which is preferably cone shaped and which engages a cone shaped seat 32' normally closing the valve opening at the seat 32'. Connected to the valve 32 is a valve stem 34 which extends through the outer closed end of the casing 33 and which slides freely in the closed outer end of said casing 33. A spring 35 at one end engages an annular lug 36 projecting in-

wardly of the air chamber b and at its opposite end engages a collar 37 on the valve stem 34. This spring 35 normally holds the valve closed. It is on the suction stroke of the rotary piston carrier 14 of the compressor which opens the valve 32 and draws the fluid into the compressor through the port 10 for compression. At the bottom of the casing 33 is an opening 38 through which air may pass to the inlet port 10 when the valve 32 is open.

In the aforesaid partition α is a plurality of ports 39 which establish communication between the air and gas chambers b and c , there being a supply pipe 41 by means of which pipe gasoline or other fluid may pass into said chamber c .

A piston valve 42 normally closes the ports 39 in the partition α . This piston valve is formed with a plurality of ports 43 which may be brought into register with the ports 39 in the partition α . These ports in the piston valve are differently spaced relative to the ports 39 in the partition so that as the piston valve slides first one port and then another will be opened and by varying the size of said ports I am able to gradually open the valve and gradually increase the supply of liquid fuel.

The piston valve 42 is connected to the valve stem 34 of the valve 32 by the connecting link 44 which is located between nuts threaded on the end of the piston valve and also between nuts threaded on the end of the valve stem 34. By adjusting these nuts the position of the piston valve relative to the valve 32 may be adjusted.

In the rotation of the piston carrier 14 on the first part of the suction stroke the valves 32 and 42 will be opened slightly if the piston carrier is rotating slowly and a small amount of air and liquid fuel drawn in through the port 10. The air and the liquid fuel will be increased in the casing 33 and delivered to the discharge side of the compressor and compressed in the chamber 7 and delivered to the receiver. Upon an increase of the suction stroke so that an increased amount of air is drawn in, the valve which controls the liquid fuel will be opened a little further and the proper proportion of gasoline is supplied to the air chamber to make a mixture of a predetermined and proper richness. The richness of the mixture may be readily varied by adjusting the connection 44 between the valve stem 34 and the piston valve 42.

To regulate the amount of intake of air and consequently the amount of gasoline, the supply of the latter being controlled by the amount of air passing through the casing 33, it may be desired to provide the intake of the air chamber with a butterfly valve 4 which governs the supply of fluid to the mixing chamber.

What is claimed is:

1. In a device such as described, the combination with an inlet chamber, of a casing in communication therewith, a yieldable 5 valve stem slidable through said casing, a valve controlling said communication, said casing having a partition therein, inlet and outlet means for said casing arranged upon opposite sides of the partition, said partition having a plurality of different sized openings formed therein, a slide movable through said casing adjacent the partition, said slide having openings of unequal size formed therein, and an operative connection 10 between said valve and valve stem.

2. In a device such as described, the combination with a mixing chamber, of a casing in communication therewith, said casing having two compartments therein separated 20 by a partition, said partition having openings of unequal size, arranged in progressive relation to each other, a valve stem movable through said casing upon one side of the partition, a valve carried by said 25 valve stem and closing the communication between said casing and mixing chamber, a spring for normally seating said valve, a slide movable in one compartment of the casing and engaging the partition, said slide 30 having spaced openings therein of different sizes arranged in progressive order similar to the openings in the partition, inlet and outlet means for said casing provided upon opposite sides of the partition, and a connection between said slide and valve stem 35 for operating the slide upon movement of the stem.

3. A mixing device for fluids comprising a casing provided with a partition in its 40 upper portion dividing the casing into gasoline and air chambers, said partition having a plurality of ports progressively increasing in size from the inner to the outer end of the casing, the air chamber being open ended 45 with its openings below said partition, a valve normally closing the discharge end of the air chamber and having its stem extending through the outer end of said casing, a valve at the inlet end of the air chamber 50 to control the supply of air to the air chamber, a piston valve projecting through the outer end of the casing and slidable in the gasoline chamber on said partition and provided with a plurality of apertures which 55 progressively increase in size from its inner

to its outer end and which correspond with the apertures in said partition, an adjustable connection exteriorly of the casing and connecting the outer ends of the said valve stem and said piston valve, so that upon 60 movement of the valve at the inner end of the air chamber said piston valve is adapted to move accordingly and bring its apertures progressively into registration with the ports in said partition to supply gasoline 65 to the air chamber through the varying sized ports in said partition according to the supply of air through the air chamber.

4. A mixing device for fluids comprising a casing provided with a partition in its 70 upper portion dividing the casing into gasoline and air chambers, said partition having a plurality of ports progressively increasing in size from the inner to the outer end of the casing, the air chamber being open ended 75 with its openings below said partition, a valve normally closing the discharge end of the air chamber and having its stem extending through the outer end of said casing, a valve at the inlet end of the air chamber 80 to control the supply of air to the air chamber, a piston valve projecting through the outer end of the casing and slidable in the gasoline chamber on said partition and provided with a plurality of apertures 85 which progressively increase in size from its inner to its outer end and which correspond with the apertures in said partition, an adjustable connection exteriorly of the casing and connecting the outer ends of the said 90 valve stem and said piston valve, so that upon movement of the valve at the inner end of the air chamber said piston valve is adapted to move accordingly and bring its apertures progressively into registration with the ports in said partition to supply gasoline 95 to the air chamber through the varying sized ports in said partition according to the supply of air through the air chamber, and means automatically lifting the valve at the inner end of said air passage from its seat to effect operation of said piston valve with relation to the apertures in said partition.

In testimony whereof I affix my signature 100 in presence of two witnesses.

BENJAMIN F. AUGUSTINE.
